CLAIM

The ornamental design for a body-mountable fertilizer dispenser, as shown.

DESCRIPTION

FIG. 1 is a perspective view of a body-mountable fertilizer dispenser showing my new design therefor;

FIG. 2 is a top plan view;

FIG. 3 is a side elevational view;

FIG. 4 is a rear elevational view;

FIG. 5 is a right side elevational view;

FIG. 6 is a front elevational view; and,

FIG. 7 is a bottom plan view.

The cross-line shading, which is partially shown for ease of illustration represents conventional fabric and is understood to cover the entire surfaces of the container and the straps.
